US00D661424S

(12) **United States Design Patent**
Ferguson et al.

(10) **Patent No.:** **US D661,424 S**
(b4) **Date of Patent:** **** Jun. 5, 2012**

(54) **LIGHTING FIXTURE**

(75) Inventors: **Christopher J. Ferguson**, Westchester, IL (US); **Michael T. Thornton**, Burr Ridge, IL (US)

(73) Assignee: **Focal Point, L.L.C.**, Chicago, IL (US)

(**) Term: **14 Years**

(21) Appl. No.: **29/394,754**

(22) Filed: **Jun. 21, 2011**

(51) **LOC (9) Cl.** **26-99**

(52) **U.S. Cl.** **D26/120**

(58) **Field of Classification Search** 40/617, 40/553, 592; D16/101; D13/179, 180; D9/457; D12/400; D8/354, 382; D10/11; D11/79, D11/129, 125, 128, 126, 127, 124, 121, 122, D11/123; D30/133; D6/462, 403; D20/41, D20/42, 10; D25/100, 106; 362/343, 362, 362/246, 260, 256, 223, 125, 565, 647, 350, 362/102; D26/96, 95, 91, 92, 93, 28, 26, D26/27, 144, 131, 94, 126, 24, 25, 140, 141, D26/142, 143, 71, 72, 73, 74, 75, 76, 77, D26/78, 79, 81, 113, 118, 119, 120, 121, D26/122, 39, 138, 135, 139, 145, 155, 154, D26/63, 64, 65, 66, 67, 68, 84, 85, 83, 82, D26/1, 2, 3, 86, 88, 132, 133, 134, 60, 61, D26/62, 123, 124, 125

(57) **CLAIM**

The ornamental design for a lighting fixture, as shown and described.

DESCRIPTION

FIG. 1 is a bottom, front, right perspective view of a lighting fixture showing our new design;

FIG. 2 is a bottom view thereof;

FIG. 3 is a top view thereof;

FIG. 4 is a right side view thereof;

FIG. 5 is a left side view thereof;

FIG. 6 is a front view thereof;

FIG. 7 is a rear view thereof;

FIG. 8 is a bottom, front perspective view thereof;

FIG. 9 is a top, right, rear perspective view thereof; and,

FIG. 10 is an enlarged and partial bottom, front, right perspective view thereof.

The uneven-length broken lines represent unclaimed boundaries of the claimed design.

The even-length broken lines showing the remainder of the lighting fixture form no part of the claimed design.

1 Claim, 6 Drawing Sheets
